HANGER FOR TOOLS AND THE LIKE

Charles M. Burt, Detroit, Mich.

Application June 17, 1957, Serial No. 46,612

Term of patent 14 years

(Cl. D80—8)

Fig. 1 is a view in perspective of a hanger for tools and the like embodying my new design;

Fig. 2 is a side elevational view;

Fig. 3 is a top plan view;

Fig. 4 is a bottom view;

Fig. 5 is a front elevational view; and

Fig. 6 is a rear elevational view.

I claim:

The ornamental design for a hanger for tools and the like, substantially as shown.
